(57) **CLAIM**

The ornamental design for a trolley case, as shown and described.

DESCRIPTION

FIG. 1 is a perspective view of a trolley case showing my new design;

FIG. 2 is a rear and bottom view thereof;

FIG. 3 is front view thereof;

FIG. 4 is rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view of the trolley case of FIG. 1, shown in a collapsed position; and,

FIG. 10 is a bottom perspective view thereof.

The broken lines in the drawings depict portions of the trolley case that form no part of the claimed design.
